MULTIPLE SOUND TRACK FILM SELECTOR DEVICE

Joseph J. Rausch, Berwyn, Ill., assignor to Litho Equipment & Supply Co., Chicago, Ill., a co-partnership consisting of Emilia E. Valetti and Carmot E. Valetti

Application October 20, 1943, Serial No. 507,008.

5 Claims. (Cl. 179—100.3)

This invention relates to a selector mechanism for use in conjunction with multi-track sound films such as are used in motion picture projectors, per se, and in other devices such, for example, as in coin-operated sound movies, coin-operated musical instruments, and the like. Sound films are also now employed for conducting or affording more or less continuous musical or like entertainment and for educational instruction which may be in the form of narration or the like with or without the accompaniment of motion pictures. Moreover, such sound films are being used in certain instances for musical entertainment in place of phonographs and have the advantage over phonographs which resides in the fact that they may be employed as lengthy films which are alternately windable off from and onto the feed reel and the take-up reel of a sound projector with which they may be used and hence they may afford a longer continuous entertainment than it is possible to obtain from a phonograph record.

An object of the present invention is to provide a new and improved and relatively simple and efficient selector device for selectively picking up and translating any desired sound track of a multiple sound track film and so as to enable the sound tracks to be picked up one after the other.

Another object of the invention is to provide a novel manually operable selector device for moving the exciter lamp and the condenser lens unit of the new selector apparatus transversely across and relative to both the light gate of a sound projector and transversely across and relative to a multiple sound track film passed therethrough.

A further object of the invention is to provide a novel selector device which will positively maintain the exciter lamp and the condenser lens unit associated therewith in proper registry with a selected sound track in the sound film and relative to the photo-electric cell embodied in the light gate of the apparatus.

Other and further objects of the present invention will be apparent from the following description and claims and will be understood by reference to the accompanying drawings which, by way of illustration, show preferred embodiments and the principles thereof and what I now consider to be the best modes in which I have contemplated applying those principles. Other embodiments of the invention embodying the same or equivalent principles may be used and structural changes may be made as desired by those skilled in the art without departing from

the present invention and the purview of the appended claims.

In the drawings,

Fig. 1 is a side elevational view illustrating a preferred form of the present invention as embodied in a sound projector;

Fig. 2 is a top plan view of the sound projector shown in Fig. 1;

Fig. 3 is an enlarged central vertical sectional view of the new selector device on line 3—3 in Fig. 1;

Fig. 4 is a vertical sectional view on line 4—4 in Fig. 3;

Fig. 5 is a sectional plan view of the new selector device on line 5—5 in Fig. 4;

Fig. 6 is an enlarged sectional view on line 6—6 in Fig. 3 and illustrating the latching mechanism embodied in the selector device;

Fig. 7 is a top plan view of the condenser lens housing which is embodied in the new apparatus; and

Fig. 8 is a fragmentary view of a typical multiple sound track film with which the new selector device may be employed in a sound projector or the like.

The present invention is shown in the drawings as being embodied in a sound motion picture projector which is generally indicated at 10 and which is mounted upon a supporting base or pedestal 11 upon which an electro-audio amplifier unit 12 is also arranged, the electro-audio amplifier unit 12 being merely indicated in the drawings since the same forms no part of the present invention.

The sound projector 10 in which the present invention is shown as being embodied comprises a pair of reversible reels, namely, a feed reel 13 and a take-up reel 14 which are rotatably mounted upon supporting arms 15 and 16, and the reels 13 and 14 may be driven by means of suitable power-transmitting instrumentalities such as the power-transmission belts 17 and 18, respectively.

A multiple sound track film 19 is alternately windable off from and onto the feed reel 13 and the take-up reel 14 and, for the purpose of the present invention, the sound film 19 is being shown as embodying five sound tracks ST (Fig. 8) although it will be understood that the present invention may be employed with a sound film embodying a greater or smaller number of sound tracks.

The present invention is primarily concerned with a selector device which is used in conjunction with the light gate which is embodied in a sound projector, as 10, such a light gate being

generally indicated at 20. The sound film 19 is guided into position for movement across the light gate 20 by means of guide rollers 21 and 22 which are arranged at opposite ends of the light gate 20, and the sound film 19 is advanced across the light gate 20 by means of a film-advancing sprocket 23 which is arranged at one side of the light gate 20; the film 19 being maintained in proper mesh with the film-advancing sprocket 23 by means of guide rollers as 24, 25 and 26. The guide rollers 25 and 26 are carried by rockets 27 and 28 which, together with the rollers 25 and 26 carried thereby, are urged by springs 29 and 30, respectively, in directions to force the sound film 19 into proper engagement with the film-guiding roller 24 and the film-advancing sprocket 23.

The apparatus thus far described forms no part of the present invention and is shown in the drawings, and has been referred to hereinbefore, so that a typical environment and use of the present invention, which will now be described, may better be understood.

As pointed out hereinbefore, the present invention is concerned with a sound track selector device which is associated with the light gate 20 and the light gate 20 includes a stationary photo-electric cell 31 (Figs. 3 and 4) which is arranged in a housing or casing 32. The photo-electric cell 31 is mounted in a socket 33 and the socket 33, in turn, is mounted in a bracket 34 which is attached to a vertically extending supporting wall 35, the wall 35 being, in turn, mounted upon the supporting base or pedestal at the front of the amplifier unit 12 (Figs. 3 and 4). The socket or base 33 for the photo-electric cell is electrically connected, in a conventional way, by way of conductors 36 (Fig. 3) with the electro-audio amplifier unit 12.

As shown in Figs. 3 and 4, the bottom wall of the housing 32 for the photo-electric cell 31 is provided with a light aperture or slot 37. This light aperture or slot 37 is disposed in registry with a light aperture or slot 38 which is formed in a curved film-guiding shoe 39, and the film-guiding shoe 39, in turn, is stationarily fastened, as at S, Fig. 4, to and on the upper wall surface 40 of a generally cylindrical housing 41 which is stationarily mounted at its rear end upon the upright supporting wall 35 (Figs. 3 and 5).

A light aperture or slot 42 is formed in the upper wall 40 of the stationary housing 41, and this slot or light aperture 42 is disposed in registry with and below the light aperture or slot 38 in the film-guiding shoe 39 (Figs. 3 and 4).

A generally cylindrical sleeve or carrier 43 is slidably mounted in the housing 41 and the upper wall of this slideable sleeve 43 is provided with a boss 44 in which a socket 45 is provided. A housing or mounting 46 for a condenser lens unit 78 is mounted in the socket 45 and this housing 46 has a reduced upper end portion 47 which is slidably guided in the slot 42 in the upper wall 40 of the housing 41. The condenser lens unit 78 (Figs. 3 and 4) is arranged in the housing or mounting 46 but inasmuch as both the condenser lens unit 78 and its housing 46 are of conventional design a detailed description thereof is deemed unnecessary. It will be understood, however, that the upper wall 47 of the condenser lens unit housing 46 is provided with a light aperture or slit 77 (Fig. 3) through which light may pass from the condenser lens unit 78 through the upper portion of the slot 42, through the slot 38, through the selected sound track in the sound

film 19, through the slot 37, into the housing 32 and thence into the photo-electric cell 31.

A clamping screw 48 is threaded into an opening 49 tapped in the boss 44 and the inner end portion of this clamping screw 48 bears upon the wall of the focusing lens housing 46 (Fig. 3).

An electric exciter lamp 50 is arranged within the slideable sleeve or carrier 43. This exciter lamp 50 is mounted in a socket 51 which, in turn, is mounted upon the rear wall 52 of the slideable sleeve 43 (Fig. 5) and the socket 51 has an electrical connection, as 53, to a suitable current source (not shown).

The rear end portion of the housing 41 is provided with a pair of bosses 54 and formed in each of these bosses 54 is a socket 55 (Fig. 5).

A pair of guide lugs or pins 56 are attached to the rear wall 52 of the slideable sleeve or carrier 43 (Fig. 5) and each of these guide lugs 56 projects into and is slidably guided in one of the sockets 55. A coil spring 57 is arranged in each of the sockets 55 and these springs 57 normally urge the slideable sleeve or carrier 43 and the exciter lamp 50 and the condenser lens unit 78, and its housing 46—47 carried thereby outwardly, that is to say, from right to left as seen in Fig. 3, or from top to bottom as seen in Fig. 5.

The generally cylindrical housing 41 includes a removable and flanged end closure wall 58 which is detachably secured to the body of the housing 41 by suitable fastening elements such as the thumb screws 74 (Fig. 5).

The closure wall 58 of the housing 41 has an outwardly projecting boss 69 formed thereon and provided in this boss 69 is a bearing opening 75 in which a rotary shaft 59 is journaled. A circular cam 60 is mounted upon the near end portion of the rotary shaft 59, and rearwardly of the inner surface of the closure member or end wall 58 of the housing 41, as shown in Fig. 3. The cam 60 has an inwardly projecting annular skirt (Figs. 3 and 5) and the inner edge of this skirt provides a spiral cam surface 61. As shown in Figs. 3 and 5 the spiral cam surface 61 of the cam 60 terminates in a rearwardly projecting stop arm 62 which normally bears upon the head 63 of a bolt 64 which is threaded into a tapped opening 65 in the boss 44 of the sleeve or carrier 43 (Fig. 3).

A row of radially arranged latch openings or slots 70 are formed in the boss 69 of the wall 58 (Figs. 3 and 6) and a socket 71 is formed in the rotary shaft 59. A latch element in the form of a latch ball 72 is arranged in the socket 71 and this latch element or ball 72 is urged radially outwardly in the socket 71, and into wiping engagement with the inner surface of the wall 69, by means of a coil spring 73 which is arranged in the socket 71 (Fig. 6).

A circular selector dial or cap 66 is mounted upon and fixed to the rotary shaft 59, by means of a suitable fastening element, such as the bolt 76, and numerical or other sound track selector indicia, as 67, are provided upon the peripheral surface of the selector dial 66 (Fig. 5), to indicate corresponding sound tracks ST on the film 19 (Fig. 8).

A pair of spaced finger grips or knobs are provided on the selector dial 66, each of these knobs being in the form of a screw having a knurled head 68 (Figs. 3 and 5).

The use and operation of the present invention are as follows: The springs 57 normally urge the slideable sleeve or carrier 43 in a direction (right to left, Fig. 3) to dispose the head 63 of the bolt

66 (Fig. 3) in contacting engagement with the spiral cam surface 61 of the rotary cam 60. Accordingly, when the head 63 of the bolt 64 is engaged with the spiral cam surface 61 of the rotary cam 60, and when the stop arm 62 of the cam surface 61 is also engaged with the head 63 of the bolt 64, as in Fig. 3, the light aperture or slit 77 in the upper end portion 47 of the condenser lens housing 46 is disposed in registry with one of the outer sound tracks in the sound film 19 and which may be identified as the No. 1 sound track. In this arrangement of the parts the numerical indicium "1" on the rotary selector dial 66 is disposed in the position in which it is shown in Fig. 5, namely, at the top and center of the dial so as to indicate the particular sound track on the film which has been selected. The entire length of the sound film 19 may then be run, through the light gate 20 in the projector 18 so as to reproduce the selected sound track. During this operation light from the exciter lamp 50 passes through the condenser lens unit 78 and through the light aperture or slit 77 in the upper end portion 47 of the condenser lens housing 46, thence through the upper end portion of the slot 42, through the light aperture or slot 38 in the film guide shoe 39, thence through the selected No. 1 sound track in the sound film 19, and then through the slot 37 into the photo-electric cell 31. In this manner the photo-electric cell is energized and translates variations from the sound track into corresponding variations of electrical current in the photo-electric cell 31. Such electrical current variations in the photo-electric cell 31 are thereupon passed, by way of the conductors 36, into the electro-audio amplifier unit 12 by which such variations in electrical energy in the photo-electric cell 31 are reconverted or retranslated from electrical energy or impulses into corresponding audio variations or sounds which are amplified by the electro-audio amplifier unit 12, in a manner which is well understood in the art.

After the selected No. 1 sound track on the film has thus been run through the light gate 20, and translated and reproduced, the film 19 may be reversed and rewound, or merely reversed, in a manner and by means well understood in the art, whereupon the slideable carrier sleeve 43 and the exciter lamp 50 and the condenser lens housing 46-47 and the condenser lens unit 78 carried thereby may be shifted in and relative to the sound film 19 and the sound tracks therein so as to bring the light slit 77 in the upper end portion 47 of the condenser lens housing 46 into registry with the No. 2 or other selected sound track in the sound film 19. This is accomplished by manually grasping one of the hand knobs 68 on the selector dial 66 and rotating the selector dial 66, and its supporting shaft 59, and the circular cam 60 carried thereby a predetermined circumferential distance (counterclockwise, as seen in Fig. 5). During this operation the head 63 of the bolt 64 rides over and down the spiral cam surface 61 on the rotary cam 60, out of engagement with the wider portion of the skirt of the cam 60-61, and into engagement with the narrower portion thereof. During this movement of the rotary cam 60-61 the head 63 of the bolt 64 is maintained in engagement with the spiral cam surface 61 of the rotary cam 60, under the action of the springs 57, and the springs 57, acting upon the lugs 56, urge the sliding sleeve or carrier 43 and the parts carried thereby,

(right to left, Fig. 3), thereby moving the exciter lamp 50 and the condenser lens housing 46-47 and the condenser lens unit 78 carried thereby relative to the light aperture or slot 42 and the sound film 19. This moves the light aperture or slit 77 in the upper end portion 47 of the condenser lens housing 46 into registry with the No. 2 (or other selected) sound track on the sound film 19.

As the rotary selector dial 66 and the rotary shaft 59 and the rotary cam 60-61 carried thereby are thus rotated a predetermined circumferential distance sufficient to move the light aperture or slit 77 in the condenser lens housing 46-47 into registry with the selected sound track in the film 19 the spring 73 in the socket 71 (Fig. 6) urges the latching detent or ball 72 into latching engagement with a corresponding one of the latch openings 70 in the annular wall 69 of the closure member 58 and this latching engagement of the parts 72-10 retains the light aperture or slit 77 in proper registry with the selected sound track on the film 19.

After all or any lesser selected number of the sound tracks in the film 19 (five being shown) have been translated and reproduced the head 63 on the bolt 64 will be disposed in engagement with the narrowest portion of the skirt on the rotary cam 60 and the numeral "5" on the selector dial 66 will be disposed uppermost and centrally on the selector dial 66. However, rotary motion imparted to one of the knobs 68 and the selector dial 66 and cam 60 will force the latching detent or ball 72 out of latching engagement in one of the latch slots 70 whereupon the shaft 59, selector dial 66 and the rotary cam 60 may then be rotated in a direction to bring the widest portion of the cam surface 61 and the stop arm 62 into engagement with the head 63 of the bolt 64. This movement of the cam 60 acts, through the bolt 63-64, to move the sliding sleeve or carrier 43 and the exciter lamp 50 and the condenser lens housing 46-47 and the condenser lens unit 78 carried thereby back into their normal and initial position, as in Fig. 3, and in which position the light aperture or slit 77 in the upper end portion 47 of the condenser lens housing 46 is disposed in registry with the No. 1 sound track on the film 19.

The present invention thus provides a novel but simple and efficient selector device for use in conjunction with sound motion picture projectors, coin-operated sound movie projectors and the like, for easily and readily enabling any one, and successively all, of the sound tracks in a sound film to be picked up and translated and reproduced into sound, and for maintaining the exciter lamp and condenser lens units 46-47-77-78 in proper registry with the selected sound track upon the sound film.

It will thus be seen that the present invention accomplishes its intended objects and has the desirable advantages and characteristics including those which have been specifically pointed out hereinbefore as well as others which are inherent in the invention.

I claim:

1. A sound film track selector device comprising a supporting frame, a photoelectric cell stationarily mounted upon said supporting frame, a housing enclosing said photoelectric cell and stationarily mounted on said supporting frame, said photoelectric cell housing including a lower wall having an elongated light slit formed therein, a

second housing stationarily mounted upon said supporting frame below said photoelectric cell housing and including an upper wall having an elongated light slit formed therein in registry with but below the said elongated light slit in the said lower wall of said photoelectric cell housing, a film-guiding shoe mounted upon the said upper wall of said second named and stationary housing and having an elongated light slit therein in registry with the said light slit in the said lower wall of said photoelectric cell housing and in registry with the said light slit in the said upper wall of the said second named housing but between the said first and second-mentioned light slits, a carrier slidably mounted in the said second named housing for movement in a direction parallel to the long axes of the said elongated light slits, an exciter lamp mounted in the said second named housing and upon the said carrier for slidable movement therewith, a part of the said lower wall of said photoelectric cell housing being spaced slightly above the said film-guiding shoe and above the said upper wall of the said second named housing and cooperating therewith to provide a film gate through which a multiple sound track film may be run in a direction transverse relative to the long axes of the said elongated light slits, a condenser lens unit mounted upon the said carrier between the said registered light slits and the said exciter lamp for directing a beam of light from the said exciter lamp through the said registered light slits and through a selected sound track of a sound film run through the said film gate, and means including a manually operable selector member affixed to a shaft and carrying therewith radially outwardly projected latching means rotatably mounted upon a wall of the said second named housing within a fixed hollow boss which is provided with a series of spaced radially disposed latch receiving openings adapted for registry with the said latching means for selectively sliding the said carrier and the said exciter lamp and the said condenser lens unit carried thereby within and relative to the said second named housing and in a direction parallel to the long axes of the said elongated light slits and relative to the said stationary photoelectric cell and its housing so as to focus the said condenser lens unit selectively upon any one of the sound tracks in a multiple sound track film passed through the said film gate, whereby upon rotation of the shaft and the latching means carried thereby and the cam selector which effects movement of the carrier, the par-

ticular sound track will be selected and the latching means on the shaft will automatically register with and engage one of the latch receiving openings within the hollow boss, thus fixing the carrier with respect to the particular selected sound track on the film.

2. A sound film track selector device as defined in claim 1 in which the condenser lens unit includes a condenser lens housing having an upper end portion extending into and slidably guided in the said elongated light slit in the said upper wall of the said second named and stationary housing.
3. A sound film track selector device as defined in claim 1 in which the condenser lens unit includes a condenser lens housing having an upper end portion extending into and slidably guided in the said elongated light slit in the said upper wall of the said second named and stationary housing, and in which the said condenser lens housing has a light aperture formed therein in registry with the said light slit in the upper wall of the said second named and stationary housing and in registry with but below the said light slit in the said film-guiding shoe and the said light slit in the said lower wall of said stationary photoelectric cell housing.
4. A sound film track selector device as defined in claim 1 in which a part of the lower wall of said stationary photoelectric cell housing rests upon a portion of the upper wall of said second-named stationary housing, and in which a portion of the upper wall of said second-named and stationary housing cooperates with a portion of the said lower wall of said stationary photoelectric cell housing to provide a wall defining one side of said film gate.
5. A sound film track selector device as defined in claim 1 in which a part of the lower wall of said stationary photoelectric cell housing rests upon a part of the upper wall of said second-named stationary housing, and in which a portion of the upper wall of said second-named and stationary housing cooperates with a portion of the said lower wall of said stationary photoelectric cell housing to provide a wall defining one side of said film gate, and in which the spacing of a part of the lower wall of said photoelectric cell housing from the upper wall of said second-named and stationary housing provides an open throat through which a sound film may be moved laterally into and out of said film gate.

JOSEPH J. RAUSCH.
